UNITED STATES PATENT OFFICE.

JULIUS FISCHL, OF NEW YORK, N. Y.

BUTTON.

Application filed December 4, 1924. Serial No. 753,919.

To all whom it may concern:

Be it known that I, JULIUS FISCHL, a citizen of the United States, residing at New York, in the county of New York and State 5 of New York, have invented certain new and useful Improvements in Buttons, of which the following is a specification.

The present invention relates to buttons and methods of manufacturing the same.

10 More particularly, the invention relates to the provision of novel shapes and methods of manufacture for loop shank buttons which are adapted for use on garments, such as men's, ladies' and children's coats, dresses, 15 garments and clothing, where a button ornamental in appearance, and the head of which will lie close to the garment surface so that the shank is invisible is highly desirable.

I am aware that loop shank buttons for 20 uniforms, in which the head lies close to the garment have been proposed. These buttons have, however, been made with heads built up in sections or a plurality of pieces, and have been necessarily of such large size due 25 to the structure thereof, that they have found use only in uniforms or as large coat and like buttons and have not been available for the garments, as set forth above, to which my improved buttons are adaptable.

30 A further serious objection to the prior built up loop shank uniform buttons is that the expense of manufacture thereof is prohibitive for garments in general, and the built up structure is mechanically unsuited 35 for such general use.

I am also aware that loop shank buttons with relatively small heads formed of one piece material, the shanks of which are secured by imbedding the ends of the loop in 40 the material of the head have been provided. These buttons have however been of such shape as to be suitable only for use on shoes, gaiters, and like articles due to the fact that when sewed in place the protruding shank 45 is plainly visible. When used on garments these buttons hang downward and are unsightly in appearance.

In my improved buttons, I have overcome 50 the objections above set forth to the use of the prior loop shank buttons for general garment use by providing a loop shank button with a one piece medium sized head which can be made of any size, shape or design desired. The head is provided with 55 a special shaped back, and a loop shank of special proportions is riveted in the button

head. By my improved method of forming these buttons, I am enabled to manufacture the same in rapidly and in large quantities.

The objects of my invention are to provide loop shank buttons suitable for general garment use; to provide novel methods of producing the same, and such other objects as may appear in the following detailed description of the invention and as set forth in the terms of the appended claim.

Referring to the drawings—

Fig. 1 is a view showing the back of a form of my improved buttons.

Fig. 2 is a sectional view of a preferred 70 form.

Fig. 3 is a sectional view of a modified form.

Fig. 4 is a plan view of a disc from which the button heads are formed.

Fig. 5 is a side elevation of the disc shown 75 in Fig. 4.

Figures 6 and 7 show the split male forming die in open position with the wire to 80 form the shank in position.

Figures 8 and 9 are views showing the male formation die closed and the disc interposed between the male and female die.

Figures 10 and 11 show the dies closed 85 together to form the button.

The improved button comprises a relatively flat head 1, or a head of any shape or pattern desired, made of cardboard, papier mâché fiber or like material in which a loop shank is firmly imbedded, and is secured by having the ends thereof upset and flattened or riveted, flush with or just beneath the outer surface of the head. The material of the head, while soft and pliable, is pressed into the desired shape as the riveting or upsetting of the ends of the loop shank occur, and the back of the button is simultaneously dished inward in specially spaced depression 3. The simultaneous riveting and forming of the head is carried out under such pressures that the head is pressed into a hardened compact unitary mass with the material securely packed and compressed around the upset ends of the loop shank. This effect is highly important 100 in making a strong button.

A further special feature of the button is the shape into which the back is pressed and the relative length of the protruding shank with relation to the size of the head. 110 The shank 2 protrudes slightly beyond the rear edge or rim of the back of the button

and just enough to permit a needle to be passed through the shank. To facilitate the sewing of the button rapidly and securely in place, the depression 3 is dished inward from as shown in Fig. 2 in such manner as to form a relatively wide clearance for the needle, and is so shaped that the needle point will be gradually guided outward toward the button rim without interference by projections on the dished back. This shape may be varied somewhat as for example by making the depression in the shape of curve, or as shown in Fig. 3, an additional central recess 4 with suitably sloping sides may be provided. The head of the button is of such diameter or size in proportion to the protrusion of the shank that when the button is sewed in place, the shank is hidden from view.

To form my improved button rapidly I have devised special methods of manufacture. I prefer to use a split male die comprising halves 5 and 6. Half 6 has formed integrally thereon a pin 7 (Figs. 6 and 7) which when the die is closed fits into a slot 8 in half 5. In operation, a short straight piece of wire 9 of proper length to form the finished shank is inserted between the open halves of the male die as shown in Figures 6 and 7, and the die is closed as shown in Figures 8 and 9. Closing the male die in this manner bends wire 9 into a U-shaped staple which is held securely in place. Depressions 10 are formed in the male die in such manner, that the desired form of depression in the back of the finished button is secured, and slot 8 and pin 7 are so proportioned with relation to depressions 10 that the proper protrusion of the shank beyond the button back is provided. A disc 11 of soft pliable cardboard, papier mâché, fiber, or like material is then interposed

and just enough to permit a needle to be passed through the shank, as shown in Figures 8 and 9, and a female die provided with a recess 13 shaped to give the desired form of button face is used to force disc 11 over the ends of the shank. As the die 12 moves toward the male die, it impacts against the ends of the shank causing these ends to be turned back, flattened and upset. The disc 11 is then impacted or forced and compressed into a hardened head of the proper shape as shown in Figures 10 and 11. The die 12 is now withdrawn, the halves 5 and 6 of the female die are separated, and the formed button is removed from pin 7.

The button is now preferably enameled, lacquered or painted to provide a suitable color and to cover the ends of the shank, if visible, in the front of the button. The button is complete.

Having described preferred embodiments of the invention, what is desired to be secured by Letters Patent and claimed as new is:

A garment button comprising a one piece head of compressed material, a shallow central depression in the back portion of said head shaped to guide the point of a needle without substantial interference across the back of said head; a loop shank seated in said central depression and protruding slightly beyond the back of said head with the ends thereof flattened or upset adjacent the front surface of said head; the size of said head being so proportioned with relation to the amount of protrusion of said loop shank that when the button is sewed to a garment said head will set close to the material and said shank will be invisible.

In testimony whereof, I affix my signature.

JULIUS FISCHL.
